SEPARATING DEVICE

Filed Feb. 13, 1922

Patented Oct. 16, 1923.

1,471,131

UNITED STATES PATENT OFFICE.

WILLIAM M. ADAMSON, OF NEW BRIGHTON, NEW YORK.

SEPARATING DEVICE.

Application filed February 13, 1922. Serial No. 536,181.

To all whom it may concern:

Be it known that I, WILLIAM M. ADAMSON, citizen of Great Britain, and resident of New Brighton, Staten Island, in the county 5 of Richmond and State of New York, have invented certain new and useful Improvements in Separating Devices, of which the following is a specification.

This invention relates to separators designed to separate material such as potatoes according to size. It is one object of this invention to provide a device whereby as many subdivisions as desired may be obtained. A further object of this invention is the provision of a separating device whereby material of the same size may be rapidly separated and automatically deposited in containers or sacks.

Still another object is the provision of a simple device by the aid of which a single operator in a given time may separate into a plurality of sizes and collect in suitable containers a quantity of material which would require the services of several operators for a similar time without the aid of this device.

Other objects and advantages will hereinafter appear.

In the accompanying drawings:

30 Fig. 1 is a perspective view of the device forming the subject of my invention.

Fig. 2 is a front view of an enlarged detail showing the means for governing the longitudinal movement of the shaker.

35 Fig. 3 is a side view of the device shown in Fig. 2.

Fig. 4 is a side view, partly sectioned, showing an enlarged detail of the pivotal connection of the shaker to the main frame.

40 Referring to the drawings there is shown a separator comprising a stationary frame and a shaker pivotally connected thereto. The stationary frame comprises two side frames 10 and 11 connected at the rear by 45 upper and lower cross-bars 12 and 13 and at the front by lower cross-bar 14. The upper rails of frames 10 and 11 are connected by intermediate rails 15, 16 and 17.

The cross-bar 16 is connected to the upper 50 rear cross-bar 12 by a centrally and longitudinally positioned bar 18. The stationary frame is thus a strong, rigid body covering a substantial area and thus insuring stability.

55 The shaker comprises a substantially U-shaped frame 20, the curved portion being

at the top and to the rear of the stationary frame, the legs of the U being interconnected by front and rear cross-bars 22 and 21. A vertical side wall 25 is supported upon the U-shaped frame and extends forwardly of front cross-bar 22. A base board 26 interconnects that portion of the side wall which extends forwardly of cross-bar 22 at each side of the U-shaped frame to 60 form a chute. In the U-shaped frame, to the rear of chute 26, is fixed a series of cross-wires forming a sieve having a variable mesh. In the rear of the shaker are positioned supporting members 30 which 65 may also be wires. Forwardly thereof the openings formed in the screen by the cross-wires 31 and 32 and 33 and 34 increase progressively in size, so that the smallest size of material is first separated. While 70 openings of but two sizes have been shown in the drawings it will be understood that the screen may be provided with any desired number of sizes of openings. The material of largest size unable to pass through any 75 of the sieves will be carried out by chute 26.

The material falling from the various-sized openings may be caught by chutes and directed into containers and sacks. In the present case chutes are provided to 80 direct the material to both sides of the stationary frame, the chutes 40 and 41 on one side and the chutes 42 and 43 on the other side being positioned at their inner ends on the central longitudinal bar 18 and 85 supported near their outer ends upon rails 44 and 45 on the side frames. The chutes direct the material into sacks such as 46 which may be supported upon U-shaped frames 47 and 48 fixed to the side frames 90 and projecting outwardly therefrom. The shaker extends slightly beyond cross-bar 17, so that material falling over chute 26 may be deposited in sacks supported upon the side frames 10 and 11 and upon an 95 upper, central rod 49 projecting forwardly from cross-bar 16.

It is thus apparent that by operating the shaker longitudinally and laterally the material will be fed downwardly and will drop through the proper mesh. Sticking of the material in the sieve may be prevented by a slight reciprocatory or jarring movement vertically. To permit such operation of the shaker it is mounted upon the stationary 100 frame by means of a U-shaped member or yoke 55 journaled on cross-bar 16. The U-

shaped member or yoke is carried at the end of a central, longitudinal bar 56 of the U-frame 20 by a loose swivel connection 51 (see Fig. 4), so that the entire shaker is free to rotate laterally about the axis of rod 56 and is capable also of slight reciprocatory movement vertically. This lateral movement is limited by stops 57 on the side frames 10 and 11. The pivotal mounting of the yoke upon cross-bar 16 and the swivel connection between the bar 56 and the yoke form a universal joint which permits rotation of the shaker laterally and vertically. Intermediate its length the bar 56 operates in a sleeve 60 having a lost-motion connection with a head 61 at the upper end of a plunger 62 operating in and extending through sleeve 63. The lower end of plunger 62 extending through sleeve 63 has fixed thereto a lock-nut 64. The sleeve is fixed in position upon bar 15 of the stationary frame, said bar extending through a sleeve 50 offset from and at right angles to sleeve 63 (see Fig. 2). It will be apparent that vertical rotation of the shaker about the axis of rod 16 will cause plunger 62 to alternately descend and rise in the sleeve 63. The rise of the shaker is limited by the stops 57 and the descent is preferably against the action of a restoring spring 65 interposed between head 61 and sleeve 63, while the upward movement of the shaker is limited also by the lock-nut 64 engaging the lower end of sleeve 63. The sleeve 60 is held against radial movement relative to bar 16 since it forms part of the cross-piece 66 mounted on cross-bars 67 and 68 fixed to the side-rails of the U-frame 20, and therefore to allow for the circumferential movement of the shaker, a pin 70 carried by head 61 operates in a slot 71 in a depending portion 72 carried by the sleeve 60.

In addition to rotation laterally and vertically, the shaker may be reciprocated vertically by providing the yoke 55 with elongated or oval slots whereby it is journaled upon rod 16 and by providing the loose swivel connection 51, so that a vibratory movement is obtained.

In operation, it is only necessary to place the material which is to be graded according to size upon the shaker at the upper portion thereof upon the wires 30. By operating the shaker as described above, that is, by rotating it laterally and vertically and reciprocating it vertically, the material is

fed over the shaker and is well distributed, so that the material will pass through the proper mesh into the corresponding chute which directs it into the bag or container. 60

If it is desired to close any part of the shaker to prevent distribution of material to openings beyond a predetermined point, there may be employed folding shutters or gates 80 and 81 carried by a collar 82 slideable upon rod 56. When stretched to their full length, these gates extend to the sides of the shaker and effectively prevent passage of material beyond them. 70

The above description illustrates a preferred embodiment of my invention, but it will be understood that various changes may be made within the scope of the annexed claims. 75

Claims:

1. A device for separating material according to size comprising a shaker, a support, and means for movably connecting said shaker to said support so that said shaker may be rotated laterally and vertically and reciprocated vertically, said means comprising a bar carried by said shaker, a yoke in which said bar is swivelled to permit rotation laterally, said support comprising a cross-bar, said yoke being pivoted on said cross-bar to permit rotation of said shaker vertically, said yoke having elongated openings through which said cross-bar extends, said openings permitting vertical reciprocatory movement of said shaker. 80 90

2. A device for separating material according to size comprising a shaker having various-sized openings increasing in size progressively from its upper end to its lower end, a support, and means for movably connecting said shaker to said support so that said shaker may be rotated laterally and vertically and reciprocated vertically, said means comprising a bar carried by said shaker, a yoke in which said bar is loosely swiveled to permit rotation laterally and reciprocation vertically, said support comprising a cross-bar, said yoke being pivoted on said cross-bar to permit rotation of said shaker vertically, said yoke having elongated openings through which said cross-bar extends, said openings permitting vertical reciprocatory movement of said shaker. 100 105

Signed at New York city, in the county of New York and State of New York, this 7th day of Feb., A. D. 1922.

W. M. ADAMSON.
